UNITED STATES PATENT OFFICE.

JOHN T. MEATS, OF TAUNTON, MASSACHUSETTS, ASSIGNOR TO THE MASON MACHINE WORKS, OF SAME PLACE.

SPINNING-MACHINE.

SPECIFICATION forming part of Letters Patent No. 570,409, dated October 27, 1896.

Application filed July 15, 1896. Serial No. 599,210. (No model.)

To all whom it may concern:

Be it known that I, JOHN T. MEATS, of Taunton, county of Bristol, State of Massachusetts, have invented an Improvement in Spinning-Machines, of which the following description, in connection with the accompanying drawings, is a specification, like letters on the drawings representing like parts.

This invention has for its object to improve and simplify those parts of spinning machinery which serve to guide the roving to the rolls for drawing or reducing the material in the process of spinning.

My invention consists, essentially, in a peculiar roving-guide, it being shown as composed wholly of wire. I have also combined with the roving-guide a clamp or device for arresting the roving when the yarn being made from the roving by spinning breaks. I have also so constructed the mechanism that the means for clamping the roving may be thrown out of operation when doffing is to take place.

Roving-guides as heretofore constructed have usually been provided with trumpets, commonly made from sheet or cast metal, and in some instances where the trumpets have been dispensed with guiding-boxes, of sheet or cast metal, have been used instead.

In my invention, as I have herein chosen to illustrate it and to gain the greatest simplicity in construction, I have made my roving-guide of wire attached to the roving-bar, and I have divided the stop-lever in two parts, so that the front part, which supports the thread between the rolls and the usual guide-eye, may be moved without affecting the rear part, which is attached to the roving-clamp.

Figure 1, in section through the rolls, shows a sufficient portion of a spinning-machine with my improvements added to enable my invention to be understood. Fig. 2 is a rear or right-hand elevation of the parts shown in Fig. 1. Fig. 3 is an enlarged detail of the stationary member of the roving-clamp, and Fig. 4 shows a modified form of roving-guide adapted to control two rovings rather than one roving. Fig. 5 is a top or plan view thereof.

The roller-beam A, its stand A', and the sets of rolls A², mounted in suitable bearings

thereon, are and may be all as usual in spinning-machines.

The roving-bar B is and may be as common in spinning-machines, and in practice it may be slid back and forth longitudinally by any usual or well-known mechanism. Upon this roving-bar I have attached, by a suitable screw a, my improved roving-guide, the same consisting of a loop a', of wire, more or less contracted at its lower end to guide the roving, the lower ends of the wire being turned upwardly to be acted upon by a suitable washer or plate, to be described, (marked a².) forming part of a clamp. Coöperating with this roving-guide a' is an auxiliary guide b, the same being composed of two wires, which are placed against the roving-bar and under the washer or clamp referred to.

In practice it is usually preferred to separate the rods b b farther apart than the lower ends of the roving-guide a', to thus enable the operator to readily pass the roving through the wider space between b b when getting it into the narrower space a⁴ of the roving-guide a'. These roving-guides travel with the roving-bar and move the roving on the rolls to prevent its wearing the covering unduly.

The stands A are provided with a rod C, which constitutes a fulcrum for the two-part stop-lever c d, the said parts being loosely pivoted thereon side by side, each part having made in it a coil to surround the said rod. The part c has at its front end an eye with a portion c', on which rests the yarn y, passing from the front rolls to the usual guide-eye f, mounted on the thread-board g, the said thread when unbroken normally acting on said part c to keep its rear end c² pressed upwardly against and keep elevated the part d of the roving-clamp.

The roving-clamp consists, as herein shown, essentially, of a piece of wire bent into the form of a loop d² and located between the main and the auxiliary roving-guide, as fully represented in the drawings, the said loop having a cross-piece 3, which, when the loop descends, as will be described, due to breakage of the yarn, will clamp the roving between itself and the recessed seat h in the coöperating part a² of the washer, before referred to. The clamp d² is normally kept ele-

vated during spinning and when the thread is unbroken by the part d of the stop-lever. The opposite end of the stop-lever has a hook d^3 , and just below said hook I have provided 5 the roller-beam with a series of loops m , preferably connected together and extending from one to the other end of the frame, said loops being adapted to be turned up into the dotted-line position shown in the drawings 10 to engage said hook, the loops when engaging the hook preventing the descent of the roving-clamp, yet permitting the front part c of the stop-lever to be elevated and the guide-board turned up for the purposes of doffing. 15 During doffing it is not desirable to clamp the roving.

In case it is desired to control two rovings for each enlargement of the roll, I then shape the roving-guide as represented in Figs. 4 20 and 5, those figures showing the guide nearest the rolls and marked n as widely separated and the auxiliary guide n' substantially in line with it, the roving being passed between the legs of the auxiliary guide and outside the legs of the main guide, as represented in Fig. 5.

During spinning and while the yarn is unbroken the parts stand in the full-line position shown in the drawings and the roving-bar is reciprocated, carrying with it the main and auxiliary roving-guide; but in case the yarn breaks the front end c of the stop-lever rises, letting the rear weighted arm d drop, it pulling down with it the clamp d^2 , causing it 35 to clamp the roving between itself and the part h of the washer a^2 , the action of the rolls pulling on the yarn separating the roving and leaving an end substantially touching the rearmost rolls, so that when the operator shall 40 have taken the end of the thread from the bobbin and led it through the guide-eye and pulled down the end c of the stop-lever, the downward movement of the lever starting the machine, he can readily piece up the roving 45 in usual manner.

If the bobbins are to be doffed, the operator throws up the loops or catches m , constituting locking devices, to engage the hooks d^3 of the rear parts d of the stop-lever, and there-

after the thread-board and the front part c of 50 the stop-lever may be freely lifted without clamping the rover.

Having described my invention, what I claim as new, and desire to secure by Letters Patent, is—

55 1. The rolls, a guide-bar, and a loop-shaped roving-guide attached to said bar, combined with a roving-clamp also made as a loop and a connected stop-lever, to operate, substantially as described.

60 2. A set of rolls, a roving-bar, two roving-guides attached thereto, and arranged one behind the other, and a stop-lever, combined with a loop-shaped roving-clamp arranged between the said two roving-guides and adapted 65 to be moved to clamp and break the roving passing from one to the other of said guides when the stop-lever is not held by the thread between the front rolls and guide-eye, substantially as described.

70 3. In a spinning-machine, a set of rolls, a roving-bar provided with a roving-guide, and a seat, and a two-part stop-lever, one of which is provided with an adjustable weight, combined with a roving-clamp made as a loop and 75 jointed to the weighted part of said stop-lever, to operate, substantially as described.

75 4. A set of rolls, a thread-guide, and a two-part stop-lever, one of said parts having a hook combined with a locking device to engage said hook and render inoperative one part of the said stop-lever leaving the other part free to be moved as required for doffing the yarn, substantially as described.

80 5. The roving-bar, the seat h , and main and auxiliary roving-guides, arranged one in front of the other, all attached to said bar, combined with a loop-like clamp arranged between said guides and co-operating with said seat, and a connected stop-lever, to operate, 85 substantially as described.

90 In testimony whereof I have signed my name to this specification in the presence of two subscribing witnesses.

JOHN T. MEATS.
